Mich., assignors to Marvel Carburetor Company,
Flint, Mich., a corporation of Illinois

Application September 25, 1930, Serial No. 484,335

6 Claims. (Cl. 123—122)

This invention relates to an improved manifold heat control for carburetor type internal combustion engines.

One object of this invention is to produce a hot-spot in which the amount of exhaust heat used is thermostatically controlled and in which the thermostat is responsive to mixture temperatures only.

Another object of this invention is to produce a thermostatic control for a hot-spot capable of distinguishing between open throttle and part throttle operation of an engine, so as to maintain the mixture temperature correct for open throttle operation when the engine is in fact operating at open throttle and at the same time maintaining the correct mixture temperature for part throttle operation when the engine is actually operating at part throttle.

A further object of this invention is to produce a thermostat capable of holding the temperature of the intake mixture to within very close limits, and to do this in the face of large variations in the temperature of the air entering the carburetor.

No other temperature about an engine has so vital an effect on its performance as does mixture temperature. Experience indicates that the driving public expects an engine to perform well long before its cooling water, lubricating oil, and radiator can be warmed up. An exhaust heated hot-spot heats up very quickly and makes this possible. If the mixture is warm enough so that the fuel is properly vaporized the engine will seem to perform nicely even when the other temperatures are far below normal. If the mixture is a little too cold, too much of the fuel will be deposited on the walls of the manifold as a stream of liquid that cannot be uniformly distributed. This will result in poor acceleration, poor economy and inferior performance on the part of the engine. If the mixture is too hot the engine will lose in power, show an increased tendency toward detonation and not be able to use a normal amount of accelerating gas.

One of the difficulties which previous inventors have met with in attempts to produce a thermostat responsive to mixture temperatures has been the fact that the engine requires a very different temperature for best operation when working at open throttle from that required at light loads.

The metal in the hot-spot will inevitably have considerable heat capacity and cannot be changed quickly from one temperature to another. If the mixture passes through the hot-spot at a very slow rate, it will pick up more heat than it can

when passing through quickly. If an engine is being driven at part throttle and the throttle is suddenly opened, the mixture temperature will inevitably drop, or if the throttle is suddenly closed, it will rise just as quickly. In the case of the engine most used in connection with the development of this invention, when the throttle was suddenly closed at 1000 R. P. M. full load, and a mixture temperature of 90° F., the mixture rose to about 150°. Repeated tests indicated that the engine would reproduce these results consistently in either direction.

This inherent change in mixture temperatures is taken advantage of, as it tends to immediately establish temperatures required. The by-metal following very rapidly any change in temperature of the mixture will therefore maintain it at this temperature, whether it be for part or wide open requirements.

It has been found experimentally that this inherent rise and fall of mixture temperatures, due to going from part to full load and the reverse corresponds very closely with that required for good operation. It has also been found that the wide open or power requirements are about 85 to 100 degrees Fahrenheit.

If, therefore, we choose this temperature for power we will find that the part throttle temperatures will be about right.

There is no objection to a moderately high temperature of mixture at part throttle. Best results are obtained this way.

The best solution seems to be to let the open throttle temperature be the controlling consideration and plan to use a part throttle temperature such that when changing quickly from closed to open throttle operation the open throttle temperature will be right.

It is well understood among automotive engineers that the vacuum in the intake manifold will vary inversely with the load on the engine. In other words when the engine is operating under full load the intake manifold vacuum is very slight, while at light loads it may be as much as 19 or 20 inches of mercury. We have taken advantage of this in connection with our thermostat. A diaphragm is placed in communication with the intake manifold and arranged so that it works against a spring. When the suction is heavy the spring will be compressed. When the suction is light the spring will push the diaphragm to its outermost position.

In the preferred form of our present invention the valve controlling the exhaust gas supply to the hot-spot is not directly actuated either by

the thermostat or by the intake manifold suction, but rather by an external source of power which is jointly controlled by these two. One way of accomplishing this is to have one of a pair of electrical contact points placed on the end of a strip 5 of bi-metallic metal, and the other contact point placed so as to be influenced by the manifold suction. The idea is to have all of the exhaust gases used to heat the hot-spot when these points are 10 separated and to have the exhaust cut off when electric contact is made. A more accurate understanding of the preferred form of our invention may be had by referring to the accompanying drawings. In all of the figures presented, the 15 same number refers to the same part.

It is accordingly an object of this invention to provide a heat control system for heated intake manifolds wherein the mixture therein is maintained at a constant temperature under given 20 operating conditions and the temperature is varied over a predetermined range in response to variations in speed and load.

Other and further important objects of this invention will be apparent from the disclosures 25 in the specification and the accompanying drawings.

This invention (in a preferred form) is illustrated in the drawings and hereinafter more fully described.

30 On the drawings:

Figure 1 is an elevation of the exhaust and intake manifolding systems of an internal combustion engine incorporating one embodiment of the features of this invention.

35 Figure 2 is a central section in the principal plane of Figure 1.

Figure 3 is an enlarged section through the preferred form of temperature and pressure control elements as applied to the intake manifold.

40 Figure 4 is a section on the line IV—IV of Figure 3 with parts in elevation.

Figure 5 is a section on the line V—V of Figure 4 with parts shown in elevation.

As shown on the drawings:

45 The manifolding arrangement chosen for illustrative purposes comprises an exhaust manifold 10 having a central outstanding pocket 11 containing a heat control valve operated by a lever 12. The valve comprises a baffle plate 13, rotatable to block the exhaust manifold, together with 50 a segmental disc valve 14 controlling ports 15 in a partition forming a continuation of the exhaust passage about midway of the depth of the pocket 11. The baffle plate 13 extends on either side of 55 the disc valve 14, the front part serving as a partition between the two ports 15.

Ducts 16 and 17 extend downwardly from the 60 ports 15 to a juncture with a heating jacket 18 enveloping the T of an intake manifold 19. The manifold is fed by a riser 20 enveloped by an extension of the jacket 18 which jacket contains a partition 21 forming a continuation of the baffle plate 13. A conventionalized carburetor 22 is shown as feeding the riser, the upper part 65 of the carburetor around the throttle valve 23 being formed as a jacket 24 connecting the lower ends of the ducts 16 and 17. With this arrangement, when the exhaust control valve is in the "heat on" position of Figure 2, the exhaust 70 gases from the left half of the exhaust manifold are diverted by the baffle plate 13 through the left port 15 into the duct 16, thence downwardly into the lower connecting jacket 24 and up the duct 17 to the right hand port 15 into 75 the exhaust manifold again. When the exhaust

control valve is turned 90 degrees to the "heat off" position, the baffle plate 13 is disposed in alignment with the flow of exhaust gases and the disc valve 14 closes the ports 15, thus cutting off the flow of exhaust gases into the heating jacket. 5

The foregoing exhaust heat control system has been chosen to illustrate the application of this invention to a particular case and it is to be understood that this invention is applicable to the operation of the other forms of heat control 10 since the invention lies in the control of the mixture temperature rather than in the heating means per se.

The temperature and pressure responsive elements of this invention are applied to an unjacketed portion of the intake manifold 19 in the form of a housing indicated generally by the reference numeral 25. A bi-metal thermostatic strip 26 extends across the manifold; one end being anchored in an insulated taper plug 27 20 sealingly mounted in a boss 28, the other or free end carrying an electrical contact 29 and projecting into the housing 25 as shown in Figures 3 and 4. The position of the thermostatic strip as well as its insulated base, renders it sensitive only to mixture temperatures, since it is almost wholly in the mixture stream and the chamber 25 is also in communication with the mixture stream through the hole provided for the free end of the thermostat. 25

30 The second contact 30 cooperating with the thermostat contact 29 is adjustably mounted in a lever 31 pivoted at 32. The free end 33 of the lever is operatively engaged with a flexible diaphragm 34 clamped around its edges by a cover 35 in a suitable recess in the housing 25. This diaphragm is responsive to intake manifold suction, and inward displacement of the diaphragm, due to increased suction, serving to move the lever 31 to increase the initial separation of the 40 electrical contact points 29 and 30. The cover 35 is provided with an atmospheric vent 36 which should be small enough so that in the event of diaphragm failure the resulting air leakage into the manifold will be restricted to a volume insufficient to materially affect the mixture proportioning.

45 The diaphragm bears against a guide plug 38 slidably in a pocket 39 in the housing, and is adapted to receive a calibrated spring 40 which 50 acts to force the diaphragm outwardly, carrying the lever end 33 therewith.

An increase in mixture temperature, perhaps accompanied by a decrease in manifold suction, brings the contact points 29 and 30 together and 55 a circuit is completed from a source of electrical energy 42 through a wire 43 to the coils of an electric magnet or solenoid 44 and thence by a wire 45 to the thermostat terminal and contact points 29 and 30 to a ground on the lever 31, 60 the ground return to the source of current being indicated by a wire 46 in Figure 1. The magnet or solenoid 44 is provided with a slidably armature 47 which is directly connected to the heat control valve lever 12 by a link 48. The 65 lever 12, link 48 and armature 47 are normally held in their upper or "heat on" position by a spring 49; the energization of the magnet or solenoid pulling down on the armature to turn the heat control valve into the "heat off" position. 70

The thermostatic responsiveness of a bi-metal strip is well known so that it will be evident that a low manifold mixture temperature, with correct initial adjustments of the adjustable contact members, will serve to maintain the nor- 75

mal separated position of the contact members, thus maintaining an open circuit under which circumstances the heat control valve 12 will be held in the "heat on" position by the spring 49.

5 This will be the normal position when the engine is not in operation or is operating at a temperature below that desired in the mixture flowing past the thermostatic member.

As the temperature begins to rise in the intake manifold the bi-metal thermostat will bend, bringing the contact members together when the desired temperature has been reached. At 10 this point energy will flow through the completed electrical circuit, energizing the magnet or 15 solenoid thus turning the heat control valve to the "heat off" position.

Since it has been found that engines under power require less heat than for part load or idling operation, the mixture temperature control 20 is designed to differentiate between part throttle and full power. This is accomplished by utilizing the variations in manifold suction to vary the relative position of the contact elements to require a greater degree of heat to close the same 25 at the higher manifold depressions which exist under idling and part load conditions.

In the illustrated embodiment of the invention the lever follows the movement of the diaphragm, which is drawn inwardly by an increase in manifold depression, so that one of the contacts is moved away from the other. It will be evident 30 that when the contacts are farthest apart due to the action of suction a greater temperature will be required to deflect the thermostatic member 35 sufficiently to bring them together. Therefore, since higher temperatures are required for idling or part load conditions, the increased suction differential will move the diaphragm inwardly. In the illustrated form of the invention the spring 40 40 is so calibrated that when the temperature is required to increase it will yield to allow the diaphragm to move inwardly to the desired extent.

It will be evident from the foregoing that the mixture temperatures may be controlled within 45 practical limits, as if the desirable temperature range is known for a given engine, it merely becomes a question of calibrating the contact movement.

It will thus be seen that we have invented an 50 improved automatic heat control which maintains a predetermined temperature range in the intake mixture, which temperature is varied under varying conditions of load and speed.

We are aware that many changes may be made, 55 and numerous details of construction may be varied through a wide range without departing from the principles of this invention, and we, therefore, do not purpose limiting the patent granted hereon, otherwise than necessitated by the prior art.

We claim as our invention:

1. An intake manifold heating system for internal combustion engines, comprising a heating jacket enveloping part of said manifold, a control valve governing the supply of heat to said heating jacket, a solenoid for operating said control valve, and means for energizing said sole-

noid including a temperature responsive element, and means incorporated therewith and subject to the suction in the manifold for decreasing the temperature range with an increasing drop in the suction in said manifold.

2. An intake system for internal combustion engines, comprising means for heating the fuel and air mixture flowing through said intake system, a control valve governing the supply of heat to said heating means, a mixture temperature responsive element for opening and closing said valve, and means responsive to engine manifold suction for modifying the temperature range of said temperature responsive element, whereby to increase the operating temperature as the manifold suction increases.

3. An intake system for internal combustion engines, comprising means for heating the fuel and air mixture flowing through said intake system, a control valve governing the supply of heat to said heating means, a mixture temperature responsive element incorporating a variable temperature range for opening and closing said valve, and means responsive to the intake suction for increasing the effective temperature controlling said valve in proportion to increasing intake suction.

4. In combination, in an intake system for an internal combustion engine, a conduit for the fluids delivered to the engine, heating means for the fluids in said conduit, a control valve governing the supply of heat to said heating means and thermally sensitive mechanism associated with the fluids in said conduit for opening and closing said valve, said mechanism being associated with said conduit in such a manner as to also be responsive to the intake suction of the engine to increase the effective temperature with an increase in engine suction.

5. In combination, in an intake system for an internal combustion engine, a conduit for the fluids delivered to the engine, heating means for the fluids in said conduit, a control valve governing the supply of heat to said heating means, and thermally sensitive mechanism associated with the fluids in said conduit for opening and closing said valve, said mechanism being associated with said conduit in such a manner as to also be responsive to the fluid pressure in said conduit to increase the range of the thermostatically responsive mechanism in accordance with the pressure decrease in the fluid.

6. An intake manifold heating system for internal combustion engines, comprising a heating jacket enveloping part of said manifold, a control valve governing the supply of heat to said heating jacket, an electrical circuit including a solenoid adapted when energized to operate said control valve, a thermostatically controlled switch in said circuit adapted to energize said solenoid upon an increase in temperature, and suction responsive means for increasing the closing temperature of said thermostatically controlled switch upon an increase in suction.
